UNITED STATES PATENT OFFICE

EDWARD J. FERGUSON, OF SANTA ROSA, CALIFORNIA.

RAIL-ANCHOR.

1,076,493.

Specification of Letters Patent.

Patented Oct. 21, 1913.

Application filed April 6, 1911. Serial No. 619,293.

To all whom it may concern:

Be it known that I, EDWARD J. FERGUSON, citizen of the United States, residing at Santa Rosa, in the county of Sonoma and State of California, have invented certain new and useful Improvements in Rail-Anchors, of which the following is a specification.

The present invention relates in general to railways, and is in the nature of a rail brace or anchor, the object of the invention being the provision of a device of this character embodying novel features of construction whereby the rails will be securely held against lateral spreading or longitudinal creeping.

A further object of the invention is the provision of a rail anchor which is simple and inexpensive in its construction, which can be quickly and correctly placed in position by unskilled labor, and which comprises few and durable parts such as will readily withstand the wear and tear to which such devices are subjected when in use.

With these and other objects in view, the invention consists in certain novel combinations and arrangements of the parts as will more fully appear as the description proceeds, the novel features thereof being pointed out in the appended claim.

For a full understanding of the invention, reference is to be had to the following description and accompanying drawing, in which:—

Figure 1 is a transverse sectional view through a railroad track showing one of the rail anchors applied to the rails, portions being broken away. Fig. 2 is a top plan view of the same. Fig. 3 is a detail perspective view of one of the clamping washers. Fig. 4 is a top plan view showing a modified form of the invention, and Fig. 5 is a sectional view on the line 5—5 of Fig. 4. Corresponding and like parts are referred to in the following description and indicated in all the views of the drawing by the same reference characters.

Referring to Figs. 1 and 2 of the drawing, the numerals 1 designate a pair of rails which rest upon the usual ties 2 and may be secured thereto in the usual manner. The rail anchor comprises a pair of similar and interchangeable rods 3 which have the inner ends thereof threaded at 4 for engagement with a turn buckle 5, the outer ends of

the rods extending under the bases of the respective rails 1 and having the extremities thereof returned upwardly at 6 for engagement with the basal flanges of the rails. Locking nuts 7 are also threaded upon the inner ends of the rods so as to be tightened against the ends of the turn buckle and prevent the same from working loose after the turn buckle has been properly adjusted. The portions of the rods 3 which are disposed under the rails are enlarged as indicated at 3^a, and the inner ends of these enlarged portions are threaded at 8 for engagement with nuts 9, the said threaded portions 8 being disposed substantially under the inner sides of the rail bases. The clamping nuts are slipped freely over the inner ends of the rods 3 until they come into contact with the enlarged portions 3^a of the rods, when they are caused to engage the threads 8. Clamping washers 10 are interposed between the nuts 9 and the basal flanges of the rails, the said clamping nuts being formed with openings 11 sufficiently large to slip freely over the enlarged portions 3^a of the rods, and being also formed with transverse grooves 12 which are arranged tangential to the openings 11 and are designed to receive the inner edges of the base flanges of the rails. With this construction it will be apparent that by tightening the nuts 9 the rail bases will be clamped between the washers 10 and the returned ends 6 of the rods, and that by properly adjusting the turn buckle 5 the rails can be moved either toward or away from each other and then locked in proper position by tightening the locking nuts 7 against the ends of the turn buckle.

A slight modification is shown in Figs. 4 and 5 which may be found useful upon steep grades where there is a very strong tendency for the rails to move longitudinally under a heavy load. The rods 3 are formed as in the previous construction and are constructed with the returned outer ends 6 and the threaded portions 8 for engagement with the clamping nuts 9. Washer members 13 are fitted upon the rods 3 between the clamping nuts 9 and the rails, the lower ends of the washer members being formed with transversely disposed plates adapted to bear against a side of the adjacent tie 2, while the upper end of the washer member is extended inwardly at 15 so as to fit over a wedge member 16. This wedge mem-

ber is interposed between the rail base and the washer member and is shown as formed with teeth 17 to bite into and securely engage the rail. It will thus be apparent that 5 the wedge member will move with the rail, and that should the rail have a tendency to creep in the direction indicated by the arrow upon Fig. 4, the bearing plate 14 will be forced against the tie and the device 10 caused to grip the rail more securely by the action of the wedge member against the washer 14. This would effectively prevent any longitudinal creeping of the rails, as well as hold them against spreading.

15 Having thus described the invention, what I claim as new and desire to secure by Letters Patent, is:—

20 A combined rail brace and anti-creeping device including a pair of rods arranged transversely of the track and extending under the respective rails, the outer ends of the rods being hooked to engage the outer edges of the rail bases while the inner ends

of the rods are threaded, a turn buckle engaging the said threaded inner ends of the 25 tie rods, nuts threaded upon intermediate portions of the rods adjacent the inner edges of the rail bases, washer members fitted upon the rods between the nuts and the inner edges of the rail bases and formed with 30 downwardly extending transversely disposed bearing flanges adapted to engage the tie to prevent creeping, the upper ends of the washer members being bent laterally, and wedge members interposed between the 35 washer members and the rail bases, said wedge members being held in position by the laterally bent upper ends of the washer members and being constructed to positively engage the rails. 40

In testimony whereof I affix my signature in presence of two witnesses.

EDWARD J. FERGUSON.
